CLAIM

The ornamental design for a bowling ball bag, as shown and described.

DESCRIPTION

FIG. 1 is a front view of a bowling ball bag, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof;

FIG. 8 is a bottom perspective view thereof;

FIG. 9 is its usage state diagram;

FIG. 10 is its usage state diagram;

FIG. 11 is its usage state diagram;

FIG. 12 is a front perspective view of its component one;

FIG. 13 is a usage state diagram of its component one; and, FIG. 14 is its usage state diagram.

The broken lines in the drawings illustrate the portions of the bowling ball bag, which form no part of the claimed design.

1 Claim, 14 Drawing Sheets
